UNITED STATES PATENT OFFICE.

LUDWIG RINNINSLAND, OF MAYSVILLE, KENTUCKY.

THILL-COUPING.

SPECIFICATION forming part of Letters Patent No. 377,814, dated February 14, 1888.

Application filed October 27, 1887. Serial No. 253,511. (No model.)

To all whom it may concern:

Be it known that I, LUDWIG RINNINSLAND, a citizen of the United States, residing at Maysville, in the county of Mason, State of Kentucky, have invented certain new and useful Improvements in Thill-Couplings, of which the following is a specification, reference being had therein to the accompanying drawings.

My invention comprises a novel combination of mortised and perforated main clips, longitudinally and transversely slotted tubular case, spring-bolt, perforated secondary clip, and detachable screw-cap, wherewith a thill or shaft can be readily coupled to the fore axle 15 of a vehicle, the details of said devices and the method of operating them being herein-after more fully described, and pointed out in the claim.

In the annexed drawings, Figure 1 is a plan 20 of the under side of my thill-coupling, a portion of the case being sectioned, the spring-bolt being retracted, and the shaft being disconnected from the axle-clip. Fig. 2 is another sectionized plan, but showing the spring-bolt advanced and engaged with the thill-iron 25 head. Fig. 3 is a transverse section of the coupling, taken at the line Z Z of Fig. 1.

A represents the fore axle of any vehicle, and B is the clip, to which one of the thills is 30 to be coupled, said clip being mortised at C to admit the thill-iron head D, which latter is pierced transversely, as seen at d in Fig. 2. Furthermore, the clip B has a perforation, b, and another perforation or socket, b', for a 35 purpose that will presently appear. Cast with or attached to this clip is a tubular case or barrel, E, having a longitudinal bore, e, one end of which communicates with the perforation b, while its other end is screw-threaded 40 for the engagement of a detachable cap, F. Adapted to traverse this case is a bolt, G, which is brought into action by a coiled spring, H, that bears against the cap F, and a fixed 45 collar, g, of said bolt, said collar serving also as a secure place for attaching the handle or knob I, wherewith the bolt is retracted.

J is a longitudinal slot in the case, which slot terminates at one end with a lateral branch, j.

K is a secondary clip secured to the axle, and perforated at k to admit one end of the 50 tubular case E, the detachable cap F being screwed up snugly against said clip.

The shaft being fastened to the thill-iron head D, and the latter being inserted in the mortise C, the spring H is allowed to exert its 55 force, thereby causing the bolt G to traverse the perforations b d and enter the socket b', which act couples said shaft to the fore axle, the bolt now serving as the pivotal pin of the coupling. Furthermore, in this advanced position of the spring-bolt, the knob I is moved forward to the end of slot J, and is quite close to the clip B; but when it is desired to uncouple the shaft this knob is forced back to the opposite end of said slot and is swung 60 around into the lateral slot or branch j, as seen in Figs. 1 and 3. By this act the bolt G is so retracted as to permit the ready withdrawal of the thill-iron head D from the mortise C of clip B, as represented in Fig. 1. 70 Consequently the shaft attached to said iron is now uncoupled from the fore axle A. Finally, any approved form of "anti-rattler" may be used in connection with my thill-coupling.

I claim as my invention--

The combination, in a thill-coupling, of mortised and perforated main clip B b' C, tubular case E e, having a longitudinal slot, J, and transverse slot j, spring-bolt G H, having 80 a handle, I, secondary clip K, perforated at k to admit one end of said case, the screw-cap F, and the pierced thill-iron head D d, as herein described, and for the purpose stated.

In testimony whereof I affix my signature in 85 presence of two witnesses.

LUDWIG RINNINSLAND.

Witnesses:

JAMES H. LAYMAN,
SAML. S. CARPENTER.
